PNEUMATIC RECOCKING DEVICE FOR
MACHINE GUNS

Lucien Albert Boussel, Courbevoie, France, assignor to Societe Anonyme des Anciens Etablissements Hotchkiss & Cie., Levallois-Perret, Seine, France, a joint stock company of France

Application May 10, 1935, Serial No. 20,841
In France April 5, 1932

19 Claims.

(CL. 89—27)

The present invention concerns a pneumatic recocking device for recocking machine guns.

A device according to the invention is shown by way of example in the accompanying drawings, in which:

Fig. 1 is a transverse-section of an aeroplane wing in which is mounted a machine gun arranged according to the invention and shown in elevation.

10 Figs. 2-8 show the recocking device according to the invention on an enlarged scale;

Fig. 2 is a sectional plane of the rear (right-hand) part;

Fig. 2a is a sectional plane of the front (left-hand) part;

Fig. 3 is a vertical transverse-section on the line III—III of Fig. 2a;

Fig. 4 is a partial transverse-section on the line IV—IV of Fig. 2a;

20 Figs. 5 and 5a are elevations, partly in section, corresponding with Figs. 2 and 2a, respectively;

Fig. 6 is a partial front view (as seen from the left on Fig. 5a);

Fig. 7 is a diagrammatic longitudinal section 25 of an auxiliary locking device and

Fig. 8 is a sectional plan of a part of an emergency recocking device.

The recocking device shown in Figs. 1-8 includes, on the one hand, supports for fixing same on an aeroplane and, on the other hand, fastening means enabling a machine gun to be readily and detachably mounted thereon and adapted to hold said machine gun in a position such that it can be actuated thereby and by a mechanism 35 for actuating the trigger.

In the example illustrated, it has been assumed (Fig. 1) that the machine gun M is lodged upside down in a wing A of an aeroplane having two wing spars L¹, L². In this case, the supports 10 of the recocking device are fixed on said wing spars. The recocking device comprises a long frame C the rear portion of which is fixed on a rod 106 connected at its rear end to a rear support plate 101, while the front portion of said frame is fixed on a tube 167 connected at its front end to a front support plate 170, said plates 101 and 170 being secured to the wing spars L¹ and L², respectively.

Referring to Figs. 2 and 5, the rear end of the rod 106 forms a ball 106^a which engages a socket secured to a sliding plate 102 and is held in said socket by a sleeve 105 screwed thereon. Said plate can slide vertically on the support plate 101 secured to the rear wing spar. The position of 5 said slide plate can be adjusted by a vertical

elevating screw 103 screwed in an ear 103^a on said plate and held from moving axially by ears 103^b on the support plate 101. The front end of the rod 106 (Fig. 2a) forms an abutment 106^a for the rear end of the machine gun.

Referring to Figs. 2a, 5a and 6, the front end of the tube 167 is engaged in an eye 168^a in a sliding bracket 168 which is mounted on a horizontal traversing screw 169^a. The latter is screwed in a sleeve 168^c on said bracket and is rotatably held by ears 170^a on the support plate 170 secured to the front wing spar. Secured to or solid with said bracket and sleeve is a ring 168^b in which the barrel of the machine gun is engaged.

Referring to Figs. 2a and 3, a collar 104 is fixed to the frame of the recocking device, by an angle piece 104^a, for holding the breech part of the machine gun. Said collar has a fixed member 104^c and straps 104^b and 104^d hinged thereto. A lever 104^e is pivotally connected to the strap 104^b, and on said lever is hinged an adjustable hook 104^f which hooks onto the strap 104^b. Said hook can be adjusted beforehand, in order that the machine gun may be clamped in the desired manner. The strap 104^b carries furthermore a lock 104^g for holding the lever 104^e in the closed position. Said collar is used as follows: the hook 104^f is hooked to the strap 104^b, the lever 104^e is turned down close to the strap 104^b for tightening 30 the collar on the machine gun and the lock 104^g is turned through 90° for locking said lever in this position.

In this manner, the machine gun can be mounted onto and dismounted from the recocking device by hand, very readily. Its position relatively to the axis of the aeroplane can be adjusted by the elevating and traversing screws 103 and 169^a, respectively.

Referring again to Fig. 1, the driving member 40 R¹ of the recocking device R is adapted to engage the recocking knob B of the machine gun when said knob is in the front or uncocked position and to drive it to the rear position, shown in Fig. 1, for recocking the gun. A firing relay 45 T is also secured on the frame C with its driving member T¹ engaging the trigger D. These engagements require no handling.

The frame of the recocking device is formed of two longitudinal angle members 110 and 111 50 forming a slide for the moveable members of said device and secured together by rear and front end cross pieces 112 and 147 respectively. The moveable members comprise a sliding member 117 having a finger 117^a and a flap 117^b and

urged forwards by a spring 115 compressed between said flap and the rear end piece 112. Said finger forms the driving member diagrammatically shown in R¹ in Fig. 1 and is adapted to 5 drive rearwards the knob B, which is shown in its forward position in Fig. 5a.

Said moveable members further comprise a moveable cylinder 128, adapted to slide on a fixed piston 145, which is fixed in the front strut 147 by means of a screw thread and gasket 146. Pivoted on a pin 122 carried in the head 126 of said cylinder 128 is an arm 119 having a nose 119¹ adapted to engage a projection 117³ on the sliding member 117 and to drive the latter rearwards. The frame members 110 and 111 provide guideways, as 111¹, 111² in 111. The ends of the pin 122 slide in the guideways 111¹. The arm 119 has, near its nose 119¹, projections 120 urged laterally outwards by a spring 121 (Fig. 4) and adapted to run rearwards in the guideways 111² and forwards in the guideways 111¹, said arm then being rocked clockwise from the position in Fig. 2a. To this end, said guideways communicate with each other by oblique slopes 111³ at 25 the rear end and 111⁴ at the front end, said slopes causing said projections to be depressed and to spring out as soon as they are in the other guideways. A return spring 155 is connected between a pin 156 in the arm 119 and another pin 30 154 secured to the front strut 147 to bring again said arm and the cylinder 128 into their position of rest, shown in Fig. 2a, when they have recoiled for recocking the gun. A leaf spring 172 is interposed between the arm 119 and the head 126 35 and tends to rock said arm anti-clockwise in Fig. 2a. Another leaf spring 173 is provided on the rear strut 112, which spring is engaged by said arm at the end of a recoil stroke of same and causes it to rock clockwise (see Fig. 2).

40 The cylinder 128 provides in its head 126 a seat for an exhaust valve 124. Secured to said valve is a cup 123 which serves as a rest for the spring 125 of said valve and as a stop for a set screw 118 carried on the arm 119. When said 45 arm returns forward with its projections 120 in the guideways 111² and thus rocks clockwise about the pin 122, said screw is adapted to depress said valve for exhausting the cylinder 128 to the atmosphere.

50 The fixed piston is hollow and thus has an inner chamber. Adapted to be slightly displaced in said chamber is a unit comprising a piston 136 with a cup leather 138 and a piston rod 135. Said rod carries at its other end an operating valve 135¹ bearing on a seat 133 in the end of the fixed piston 145 in front of the head 126 to close orifices 135², through which the chamber in said piston can communicate with the chamber in the cylinder 128. A spring 144 is provided between 55 the inner piston 136 and the front strut 147 to press said piston into the fixed outer piston 145 and to close said operating valve. The inner piston 136 is also hollow and forms an outwardly open inlet chamber 145¹ so as to accommodate an inlet valve 140 having a spring 141.

60 Compressed air can be introduced into the inlet chamber 145¹ by a duct 147⁵ in the front strut 147 and through the inlet valve 140 acting as a check valve, into the fixed piston 145, where it is stored until a recocking operation is required. Alternatively, said duct can be connected to the atmosphere which causes the inner piston 136 to be displaced forwards by the pressure in the fixed piston 145 and thus to open the operating valve 135¹, whereupon compressed air

enters the cylinder 128 and causes same to recoil for recocking the machine gun.

Connection of said duct to compressed air or to the atmosphere is controlled, in the embodiment shown, by a delay mechanism. Said mechanism comprises a cylinder 157 located in the right hand part of the slide 110—111 and in which a piston valve is adapted to reciprocate, said valve having two spaced packing rings 160, 160¹ carried on the front end of a rod 160². The cylinder 157 has ports 157¹ communicating with the duct 147⁵, other ports 157² communicating with a hollow plug 161 screwed in the strut 147 and to which the compressed air feed pipe 161¹ is connected, and a slot 157³ opening to the atmosphere. Said ports and slot are so located that the rear packing ring 160 connects the ports 157¹ either with the slot 157³ or with the ports 157² and thus connects the duct 147⁵ either to the atmosphere or to the compressed air respectively, according to the valve being in its forward or its rear position (which latter is shown in Figs. 2a and 5a) respectively, while the front packing ring 160¹ forms a closure for the space which is fed through the ports 157² in any position of the valve. The arrangement is further such that said rear packing ring has to travel a distance forwards from its rear position to close the ports 157¹ and thus to cut off the admission of compressed air to the duct 147⁵, and has further to travel to the foremost position to pass said ports to connect them to the atmosphere.

45 A coiled spring 159 located in the rear end of the cylinder 157 between a screwed cap 158 and a flange 160³ on the rod 160² urges the valve 160—160¹ to the front position. A similar cap 158 screwed on the front end of the cylinder 157 has an opening 158² with a flap 158¹ adapted to entrap air before the front packing ring 160¹, 40 and to form, together with said ring, an air brake or damper for the forward stroke of the piston valve.

50 Arranged to reciprocate on the side of the slide 111 adjacent to the path of the recocking knob B is a rod 164 having a nose 164¹ at its rear end and a fork 162 at its front end. The nose 164¹ is adapted to be engaged by said knob near the end of its recoil stroke and to be driven back a distance equal to the desired stroke of the piston valve. The fork 162 protrudes in the cylinder 157 through the slot 157³ and engages the flange 160³ to drive back the piston valve against the spring 159 as the knob drives the nose 164¹.

55 It will be understood that by the arrangement described, the piston valve 160—160¹ is positively driven to its rearmost position by each recoil of the recocking knob and is slowly returned forwards by the spring 159 with the damper 160¹, 158¹, so that when the gun is firing, said valve reciprocates between its rearmost position and a 60 position a little before said rearmost position, the duct 147⁵ remaining connected to the compressed air, and when the gun stops firing with the repetition mechanism released or uncocked 65 and the recocking knob resting in its front position, said valve is allowed to return to its front position to finally connect said duct to the atmosphere, thereby to cause the piston 136 to open the valve 135¹ and thus to make the recocking cylinder 128 effect a recocking stroke.

70 However, a misfire can occur shortly after another, so that at this time the hollow piston 145 is not sufficiently filled with compressed air to enable the gun to be recocked; moreover, such 75

a misfire can occur while the cylinder 128 still effects its return stroke with the projections 120 on the rocking arm 119 engaged in the outer groove 111² of the slide 110—111, and the nose 5 119¹ of said cam disengaged from the sliding member 117. In such cases, the recocking would be missed and even no longer possible with the arrangement described, since compressed air would be no longer supplied to said hollow piston 10 ton. In order to obviate such failures, locking devices are provided which prevent the piston valve 160—160¹ from returning forwards until the desirable pressure in the hollow piston is reached and until the cylinder 128 has returned to its 15 position of rest. Said devices comprise pawls or catches 153—153¹ (Figs. 2a, 5a and 3) and 200 (Fig. 7) yieldingly engaged in the valve cylinder 157 and cooperating with a collar 160⁴ on the rod 160², the arrangement, which includes suitable bevels on said pawls and collar, being such that the slide valve 160—160¹ can move back but cannot return forwards to open ports 157¹ to the atmosphere until both of said pawls are retracted from the cylinder 157.

25 The pawl 153 is carried on a pivoting pin 152 (Figs. 2a and 3) with a spring 152¹ (Fig. 3), urging it into the valve cylinder. Secured to the same pin is a lever 149 which extends to the side of the recocking cylinder 128 and ends in a nose 30 149¹ adapted to be pushed forwards by the ring 134 on the front end of cylinder 128 when the latter is in the forward position, so that the pawl 153 is then, and only then, retracted from the valve cylinder. The pawl 200 (Fig. 7) is formed 35 by a bell crank lever 201 actuated by the rod 202 of a bellows piston 203 arranged in a cylinder 203¹, which cylinder is connected to the duct 147⁵. The pressure acts on said bellows piston in the direction of the arrow f³⁰, to retract the 40 pawl 200, and a spring 204 acts in the opposite direction, so that the pawl is only retracted when the pressure in the duct 147⁵ and therefore in the hollow piston 145 has reached the desired value.

45 The operation of the recocking mechanism is effected in the following manner: when the machine gun is cocked or is recoiling normally during firing, the recocking knob displaces the rod 164 of the delay mechanism in the direction of 50 f³; the fork 162 displaces the piston valve 160 so that the compressed air entering the valve cylinder 157 through the channels of the plug 161 is introduced into the duct 147⁵, and penetrates into the inlet chamber 145¹ of the fixed 55 piston 145.

The air introduced into said chamber 145¹ raises the inlet valve 140 and fills the piston 145 until after a misfire and, by the operation of the delay mechanism 157, 160 etc., the inlet chamber 145¹ is placed in communication with the atmosphere through the ports 157¹ and the window 157³.

At the instant when the chamber 145¹ is placed 60 in communication with the outer air, the displaceable unit, that is to say, the piston 136, is displaced in the direction of f⁴ in the inner chamber of the fixed piston 145, compressing the spring 144, thereby moving the valve 135¹ away from its seat and permitting the charge of compressed air contained in the hollow piston 145 to 70 expand violently in the displaceable cylinder 128, by passing through the orifices 135², and consequently to cause the displacement in the direction of f¹ of the displaceable cylinder 128 and 75 of the members attached thereto.

In particular, the displaceable cylinder 128 drives the arm 119 in the direction of f¹; the nose 119¹ of the arm, which abuts against the sliding member 117, carries same with it, which in turn pushes with its finger 117¹ the recocking 5 knob B of the machine gun.

In this movement in the direction of f¹, the projections 120 of the arm 119 slide first in the inner guideways 111¹, but at the end of this stroke, they are depressed by the slopes 111³, 10 pass into the outer guideways 111² and spring out therein, the arm 119 being rocked owing to said slopes and to the spring 173 on the rear strut 112. Such rocking of said arm disengages its nose 119¹ from the projection 117³ on the 15 sliding member 117, which then quickly returns forwards due to the spring 115. Said spring 173 damps the end of the recoil stroke of the cylinder 128 and accelerates its return movement. At the same instant, as said arm is rocked, the 20 set screw 118 is brought into engagement with the cup 123, and the valve 124 is lifted from its seat for exhausting the cylinder 128.

The return spring 155, which is tensioned in the travel in the direction of f¹, brings back the 25 arm 119 and the displaceable cylinder 128 in the opposite direction to f¹ into their initial position; during this return, the projections 120 slide in the outer guideway 111², whereas the pivot 122 of the cam slides in the inner guideway 111¹, so 30 that the set screw 118 remains in engagement with the cup 123, the valve 124 consequently remaining constantly open.

At the end of the travel in the opposite direction to f¹, the projections 120 of the arm 119 35 pass from the outer guideway 111² into the inner guideway 111¹ by the slope 111⁴ and under the action of the spring 172 which rocks the arm 119 in the opposite direction to f²¹; in this position the nose 119¹ of the arm 119 again engages 40 the projection 117³ of the slide 117, whereas the exhaust valve 124, which is released from the action of the set screw 118, returns to its seat and closes the displaceable cylinder 128.

The machine gun being recocked, resumes firing 45 if it had been accidentally stopped, if not, it suffices to operate the trigger D to start firing again.

The trigger can be operated by a pneumatic or other relay 181 (Fig. 3) diagrammatically shown 50 in T, T¹ in Fig. 1, and with which this invention is not concerned.

The arrangement illustrated for the remote control of a machine gun also includes an emergency device for recocking the machine gun in 55 case of failure of the pneumatic device. For this purpose, the tube 114, on which the turned-back flap 117² of a sliding member 117 is loosely engaged, is connected to the end of a flexible cable 116 passing over transmission pulleys 107¹, 107² and is adapted to slide in a tube 113 which is secured, at its rear end, in the rear strut 112.

Referring to Fig. 8, the free end of the cable 116 carries a handle 116¹ serving to actuate the cable 116 and to displace the sliding member in 65 the direction of f¹. When the handle 116¹ is pulled, the cable 116, the sliding member 117 and the recocking knob of the machine gun are operated. A safety device against an accidental operation of the trigger is combined with the cable 70 116; said device comprises a nipple 116² secured to said cable 116; said nipple 116² slides within a sleeve 116³ and engages spring-pressed pawls 116⁴, 116⁵ which hold the cable and the members it controls in a safety position. The pawls

116⁴, 116⁵ can be disengaged from the nipple 116² by means of a ring 116⁶ sliding on the sleeve 116³, said ring having springs 116⁷ which cause the pawls 116⁴, 116⁵ to swing about their pins 5 thereby disengaging the nipple for the pneumatic operation to start again.

I claim:

1. Pneumatic device for recocking a machine gun, comprising a frame, a cylinder adapted to 10 slide in said frame, a fixed hollow piston in said cylinder, adapted to contain an operative charge of compressed fluid, an operating valve in said hollow piston opening into said cylinder and adapted when closed to prevent said charge from 15 passing into the cylinder, means for feeding said hollow piston with compressed fluid, means for controlling said operating valve, means for returning said cylinder towards said hollow piston after a recoil stroke, means for connecting said frame to said gun so that said cylinder through its recoil stroke drives the machine gun recocking bolt to recock same, and means for securing the machine gun with the recocking device to a supporting structure.

2. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, a control piston adapted to actuate said operating valve, a chamber cooperating with said control piston, means for varying the pressure in said chamber to operate said control piston, means for returning said cylinder towards said hollow piston after a recoil stroke, means for connecting said frame 40 to said gun so that said cylinder through its recoil stroke drives the machine gun recocking bolt to recock same, and means for securing the machine gun with the recocking device to a supporting structure.

45 3. Pneumatic device for recocking a machine gun, comprising a frame, a cylinder adapted to slide in said frame, a fixed hollow piston in said cylinder, adapted to contain an operative charge of compressed fluid, an operating valve 50 in said hollow piston opening into said cylinder and adapted when closed to prevent said charge from passing into the cylinder, means for feeding said hollow piston with compressed fluid, a control piston adapted to actuate said operating valve, a chamber cooperating with said control piston, a distributor adapted to connect said chamber to the fluid pressure and to the atmosphere to operate said control piston, means for returning said cylinder towards said hollow piston 55 ton after a recoil stroke, means for connecting said frame to said gun so that said cylinder through its recoil stroke drives the machine gun recocking bolt to recock same, and means for securing the machine gun with the recocking device to a supporting structure.

4. Pneumatic device for recocking a machine gun, comprising a frame, a cylinder adapted to slide in said frame, a fixed hollow piston in said cylinder, adapted to contain an operative charge 70 of compressed fluid, an operating valve in said hollow piston, opening into said cylinder and adapted when closed to prevent said charge from passing into the cylinder, an inlet chamber, an inlet valve between same and said hollow piston, 75 a distributor adapted to connect said chamber

to the fluid pressure and to the atmosphere, a control piston cooperating with said chamber and adapted to open said operating valve upon said chamber being connected to the atmosphere, means for returning said cylinder towards said hollow piston after a recoil stroke, means for connecting said frame to said gun so that said cylinder through its recoil stroke drives the machine gun recocking bolt to recock same, and means for securing the machine gun with the recocking device to a supporting structure.

5 5. Pneumatic device for recocking a machine gun, comprising a frame, a cylinder adapted to slide in said frame, a fixed hollow piston in said cylinder, adapted to contain an operative charge 15 of compressed fluid, an operating valve in said hollow piston opening into said cylinder and adapted when closed to prevent said charge from passing into the cylinder, a control piston forming a floating bottom for said hollow piston, said operating valve being located in the face of said hollow piston opposite to its bottom and being rigidly connected to said control piston, so as to be opened when said control piston moves away from said hollow piston face, an inlet chamber 25 before said control piston, an inlet valve located in said control piston to let the fluid pressure pass from said inlet chamber into said hollow piston, a distributor adapted to connect said inlet chamber to the fluid pressure and to the atmosphere, means for returning said cylinder towards said hollow piston after a recoil stroke, means for connecting said frame to said gun so that said cylinder through its recoil stroke drives the machine gun recocking bolt to recock same, 35 and means for securing the machine gun with the recocking device to a supporting structure.

6. Pneumatic device for recocking a machine gun, comprising a frame, a cylinder adapted to slide in said frame, a fixed hollow piston in said cylinder, adapted to contain an operative charge 40 of compressed fluid, an operating valve in said hollow piston opening into said cylinder and adapted when closed to prevent said charge from passing into the cylinder, means for feeding said 45 hollow piston with compressed fluid, a control piston adapted to actuate said operating valve, a chamber cooperating with said control piston, a distributor having a movable member and adapted to connect said chamber to the fluid pressure and to the atmosphere according to the position of said member, in order to operate said control piston, said movable member being adapted to be engaged and driven by the machine gun recocking bolt when the latter recoils to a set position in which it causes said distributor to operate said control piston to close said operating valve, yielding means for urging said member to a position of rest in which it causes said distributor to operate said control piston for opening 50 said operating valve, means for delaying the movement of said member towards the position of rest whereby said member is slowly returned to this position when said recocking bolt rests in its forward position, means for returning 55 said cylinder towards said hollow piston after a recoil stroke, means for connecting said frame to said gun so that said cylinder through its recoil stroke drives the machine gun recocking bolt to recock same, and means for securing the machine gun with the recocking device to a supporting position. 60

7. Pneumatic device for recocking a machine gun, comprising a frame, a cylinder adapted to slide in said frame, a fixed hollow piston in said

5 cylinder, adapted to contain an operative charge of compressed fluid, an operating valve in said hollow piston opening into said cylinder and adapted when closed to prevent said charge from passing into the cylinder, means for feeding said hollow piston with compressed fluid, a control piston adapted to actuate said operating valve, a chamber cooperating with said control piston, a slide valve adapted to connect said chamber to 10 the fluid pressure and to the atmosphere to operate said control piston, so as to open said operating valve when said slide valve is in its rest position, a spring adapted to urge said slide valve towards its rest position, said slide valve being 15 pushed to its set up position by the recoils of the machine gun recocking bolt, an air damper to delay the return of said valve to its rest position, means for returning said cylinder towards said hollow piston after a recoil stroke, means 20 for connecting said frame to said gun so that said cylinder through its recoil stroke drives the machine gun recocking bolt to recock same, and means for securing the machine gun with the recocking device to a supporting structure.

25 8. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, locking means adapted to prevent said operating valve from being opened unless said cylinder is in its rest position, means for returning said cylinder towards said hollow piston after a recoil stroke; means for connecting said frame to said gun so 30 that said cylinder through its recoil stroke drives the machine gun recocking bolt to recock same, and means for securing the machine gun with the recocking device to a supporting structure.

35 9. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, pneumatic locking means adapted to prevent said operating 40 valve from being opened until the fluid in said hollow piston has reached a suitable pressure, means for returning said cylinder towards said hollow piston after a recoil stroke, means for connecting said frame to said gun so that said cylinder through its recoil stroke drives the machine gun recocking bolt to recock same, and means for securing the machine gun with the recocking device to a supporting device.

45 10. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, means for returning said cylinder towards said hollow piston 50 after a recoil stroke, an outlet valve in said cyl-

inder, means for controlling said outlet valve so as to retain it open during the return stroke of the cylinder, means for connecting said frame to said gun so that said cylinder through its recoil stroke drives the machine gun recocking bolt to recock same, and means for securing the machine gun with the recocking device to a supporting structure. 5

11. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, means for returning said cylinder towards said hollow piston after a recoil stroke, a sliding member in said frame, a driving connection between said cylinder and said sliding member and such that said cylinder drives said sliding member during its recoil stroke and that an escapement occurs at the end of said stroke, a spring to rapidly return said sliding member to its rest position after such escapement has occurred, means for connecting said frame to said gun so that said sliding member through its recoil stroke drives the machine gun recocking bolt to recock same, and means for securing the machine gun with the recocking device to a supporting structure. 10 15 20 25

30 12. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, means for returning said cylinder towards said hollow piston after a recoil stroke, an outlet valve in said cylinder, a sliding member in said frame, a rocking arm on said cylinder, a finger on said arm adapted to open said outlet valve when said arm is in an outlet position, a cam on said arm adapted to engage said sliding member to drive same through the recoil of said cylinder when said arm is in a driving position, guide means in said frame to retain said arm in driving and outlet positions during the recoil and the return strokes of the cylinder, respectively, and to rock same at the ends of such strokes, means for connecting said frame to said gun so that said sliding member through its recoil stroke drives the machine gun recocking bolt to recock same, and means for securing the machine gun with the recocking device to a supporting structure. 35 40 45 50 55 60

65 13. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, means for returning said cylinder towards said hollow piston after a recoil stroke, means for connecting said frame to said gun so that said cylinder through its recoil stroke drives the machine gun recocking bolt to recock same, a manually actuated me- 70 75

chanical transmission the end part of which is carried on said frame and is also adapted to recock the machine gun, and means for securing the machine gun with the recocking device to a supporting structure.

- 5 14. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, means for returning said cylinder towards said hollow piston after a recoil stroke, a sliding member in said frame, a driving connection between said cylinder and said sliding member and such that said cylinder drives said sliding member during its recoil stroke and that an escapement occurs at the end of said stroke, a spring to rapidly return said sliding member to its rest position after such escapement has occurred, means for connecting said frame to said gun so that said sliding member through its recoil stroke drives the machine gun recocking bolt to recock same, a rod adapted to slide in said frame and to push said sliding member in the recoil direction to recock the machine gun, a manually actuated mechanical transmission the end part of which is formed by said rod, and means for securing the machine gun with the recocking device to a supporting structure.
- 25 15. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, means for returning said cylinder towards said hollow piston after a recoil stroke, means for removably connecting said gun to said frame so that said cylinder through its recoil stroke drives the machine gun recocking bolt to recock same, and means for securing said frame to a supporting structure.
- 45 16. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, means for returning said cylinder towards said hollow piston after a recoil stroke, a ring carried by said frame and adapted to engage the gun barrel, a manually operated securing collar also carried by said frame and adapted to engage the gun breech,

said ring and collar being arranged so that said cylinder through its recoil stroke drives the machine gun recocking bolt to recock same, and means for securing said frame to a supporting structure.

5

17. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, means for returning said cylinder towards said hollow piston after a recoil stroke, means for connecting said frame to said gun so that said cylinder through its recoil stroke drives the machine gun recocking bolt to recock same, and means for securing the machine gun with the recocking device to a supporting structure, the last said means being adjustable for elevation and for direction.

10

18. Pneumatic device for recocking a machine gun, comprising a frame, a cylinder adapted to slide in said frame, a fixed hollow piston in said cylinder, adapted to contain an operative charge of compressed fluid, an operating valve in said hollow piston opening into said cylinder and adapted when closed to prevent said charge from passing into the cylinder, means for feeding said hollow piston with compressed fluid, means for controlling said operating valve, means for returning said cylinder towards said hollow piston after a recoil stroke, means for connecting said frame to said gun so that said cylinder through its recoil stroke drives the machine gun recocking bolt to recock same, and means for securing said frame to a supporting structure.
